UNITED STATES PATENT OFFICE.

ELLA W. RICHARDS, OF WASHINGTON, DISTRICT OF COLUMBIA, ASSIGNOR OF ONE-HALF TO CHARLES S. RICHARDS, OF WASHINGTON, DISTRICT OF COLUMBIA.

STOCKING STRETCHER.

Application filed November 23, 1927. Serial No. 235,353.

This invention relates to new and useful improvements in stretchers for stockings, and has for its primary object to provide a highly novel, simple, and inexpensive device that is well adapted for disposition within stockings of various sizes, after the same have been washed, so as to prevent shrinking of the same while drying.

One of the most important objects of the invention is to provide a stretcher of this character wherein the foot portion thereof may be adjusted at will to accommodate stockings of various foot sizes.

Other objects and practical advantages of the invention will be fully understood from the following description and claims when the same are considered in connection with the drawings, accompanying and forming part of this specification, in which:

20 Figure 1 is an elevation of a stocking stretcher constructed in accordance with the present invention, and

25 Figure 2 is a section taken through the foot portion thereof and substantially upon the line 2—2 of Figure 1.

Now having particular reference to the drawing, my novel stretcher consists of a plate 5 of metal or other suitable material of flat-like formation, and of a shape in silhouette substantially the shape of a human leg, the lower end thereof being formed to provide the rear half of a foot 6, the end of which is formed at its opposite edges with inwardly extending turned over spring clips 7—7 each of which is formed with a depressed lug 8. For association with the foot section of the stretcher is a plate 9 of a material similar to the material forming the main body of the device and formed at its outer end so as to simulate the toe of a foot in silhouette.

The opposite longitudinal edges of this plate 9 are formed with spaced openings 10 adjacent each of which is an indicating character to designate the length of the foot of the stretcher when said plate 9 is in predetermined adjusted position. Obviously, the lugs 8 of the spring clips 7 are for engagement within predetermined ones of the holes 10 at the longitudinal edges of the extensible plate 9 for rigidly securing said plate to the foot of the stretcher so that when the stretcher is arranged within a stocking, the

foot size of which is complementary to the prearranged size of the stretcher foot there will be little or no liability of the plate 9 moving inwardly, which would otherwise permit the foot of the stocking to shrink.

It will thus be seen that I have provided a highly novel, simple, and efficient stocking stretcher that is well adapted for all the purposes heretofore designated, and even though I have herein shown and described the invention as consisting of certain detail structural elements, it is nevertheless to be understood that minor changes may be made therein without affecting the spirit and scope of the appended claims.

Having thus described the invention, what I claim is:

1. In a stocking stretcher of the character described, a flat plate of leg shape in outline and formed at one end with an extension in simulation of a rear portion of a foot and an adjustable toe plate associated with said foot portion in a manner and for the purpose described, said toe plate being formed at its longitudinal edges with spaced openings, in-turned spring clips at the end of the foot portion and at the upper and lower edges thereof for engagement over the edges of said toe plate and pressed lugs formed in said clips for selective engagement within predetermined openings in the edges of said toe plates.

2. In a stocking stretcher and in combination, a foot portion, and a toe plate arranged along side of and extending beyond said foot portion, and retained on and adjustable lengthwise relative to the same; one of said elements having seats at intervals of its length and the other element having a projection spring pressed transversely of the foot portion and adapted for removable disposition in said seats.

3. In a stocking stretcher and in combination, a foot portion, and a toe plate arranged along side of and extending beyond said foot portion; one of said elements having seats at intervals of its length and the other spring clips straddling the seat element, with a projection on one of said clips for removable disposition in said seats.

In testimony whereof I affix my signature.

ELLA W. RICHARDS.
